OIL CRACKING PROCESS

Eugene C. Herthel, Chicago, Ill., assignor to Sinclair Refining Company, New York, N. Y., a corporation of Maine

Application February 12, 1927, Serial No. 167,716

6 Claims. (Cl. 196—55)

This invention relates to improvements in the cracking of heavier oils such as gas oil in pressure stills for the production of lighter oils such as gasoline, motor spirit or pressure distillate therefrom. The invention comprises an improved process which can be continued for a longer period of time before it is necessary to shut down for cleaning purposes.

In the cracking of heavier petroleum oils in pressure stills for the production of gasoline or pressure distillate therefrom there are formed during the cracking operation certain constituents of an asphaltic or pitch-like character. With continuation of the cracking operation, the amount of such constituents increases and there is a tendency for a deposit of carbon or coke to form on the heated surfaces of the still, thus necessitating the shutting down of the still for cleaning purposes between successive runs. The shutting down of a pressure still, the withdrawal of the charge therefrom, the cleaning of the still, the recharging of the still and the preliminary heating of the still to bring the fresh charge up to cracking conditions, all require time, and the total amount of time so required in ordinary commercial operations means a corresponding reduction in the proportion of the time when the still is operating for carrying out the desired cracking operation.

According to the present invention, the deposition of pitch or carbon on the heating surfaces of the pressure still is prevented or greatly reduced so that overheating or danger of failure of the heating surfaces can be effectively prevented, and the time of operation of a single run can be prolonged, with correspondingly greater continuity of operation, less loss of time, and greater production per still per day.

When a pressure still is charged with gas oil or other charging stock to be subjected to cracking, and when the charge is heated to an appropriate cracking temperature, the cracking takes place in a gradual and progressive manner. The lighter constituents produced by the cracking operation, which go to make up the pressure distillate, are removed from the still progressively during the cracking operation. Other constituents, such as heavier hydrocarbons formed by the cracking operation, may remain and mix with the charge of the still. A small amount of asphaltic or pitch-like constituents is progressively formed. Such constituents appear to be of varying properties and characteristics. For the most part they remain in solution in the charge during the early portion of the run, and

they may remain completely in solution during the early portion of the run. With gradual and progressive cracking of the charge, however, the amount of such asphaltic or pitch-like constituents gradually and progressively increases until sooner or later the amount of such constituents increases beyond the saturation point. Furthermore, certain of these constituents, which appear to be relatively small in amount as compared to the total amount of the pitch-like constituents formed, appear to be of a different character and to have an increased tendency to deposit on the heating surfaces of the still. Furthermore, as the charge becomes supersaturated with the less objectionable pitch-like constituents, there is an increased danger of deposit of pitch or carbon on the heating surfaces of the still, with corresponding danger of overheating and failure of the heated surfaces if the still is not shut down at more or less frequent intervals to remove this deposit.

Among the constituents produced by the cracking operation which seem to be particularly objectionable are certain sulphur-containing compounds. In charging stock which contains sulphur, certain of the sulphur compounds appear to undergo cracking to form sulphur-containing constituents, probably of an asphalt-like character, which are particularly objectionable.

Analyses of the carbon deposit on the heated tubes of a cracking still indicate that certain of these sulphur-containing constituents have a preferential affinity for the heated surfaces, or tend to separate out on such surfaces, to give a deposit containing both iron and sulphur in proportions approximating those of iron sulphide. It may be also that asphalt-like constituents of a colloidal character, or even colloidal carbon, formed as a result of the cracking operation, tend to separate out on the heated surfaces of the still in a preferential manner.

I have found that the length of time during which the operation of a pressure still can be continued can be prolonged by maintaining a quantity of finely divided fuller's earth or similar absorbent material in intimate admixture with the pressure still charge while undergoing the cracking operation. By maintaining a quantity of fuller's earth in intimate admixture with the still charge and by introducing fresh feed and withdrawing pitch-laden tar the pressure still run can be substantially prolonged.

The finely divided fuller's earth does not remove from the still charge all of the pitch-like constituents, but it has a selective action upon

certain of these constituents and apparently removes those constituents which are particularly objectionable from the standpoint of forming a carbon deposit on the heated surfaces of the still. This selective action may be a selective absorption of colloidal carbon or precipitated asphalt-like constituents, or sulphur-containing constituents, etc. Whatever the explanation of the action of the fuller's earth may be, it has an important protective effect in preventing objectionable carbon deposit. The fuller's earth also apparently has a selective desulphurizing action upon the pressure still charge, selectively removing therefrom certain of the objectionable sulphur-containing constituents of the charge. It is probable, also, that certain of the constituents of an asphalt-like character produced by the cracking operation and which tend to separate out from the charge as suspended particles are removed from the circulating charge by the selective adsorbent action of the fuller's earth.

In addition to the selective action of the fuller's earth upon the charge, the pitch content of the charge is regulated by the introduction of fresh feed and the withdrawal of pitch-laden tar, so that the content of the charge as a whole is maintained below the point which would cause objectionable carbon deposit on the heated surfaces of the still.

Accordingly, in the process of the present invention, both the nature and the amount of the asphaltic or pitch-like constituents in the charge are regulated, certain of these constituents being selectively removed by the adsorbent action of the finely divided fuller's earth, the content of remaining constituents in the charge being regulated and controlled by the withdrawal of pitch-laden tar and the introduction of fresh feed during the cracking operation.

The entire body of oil charged into the pressure still, for example, gas oil, serves to hold in solution the pitch-like constituents that are formed. In the process of the present invention, however, only the pitch-like constituents which are not removed by the fuller's earth remain to be held in solution in the charge.

In its broader aspect, the improved process of the invention can be carried out in stills of different construction, but whatever the type of still, the finely divided fuller's earth is admixed with the still charge and rapid circulation of the oil is maintained over the heated surfaces to prevent segregation and accumulation of the earth thereon and to insure the maintenance of an intimate admixture of the fuller's earth with the oil while contacting with the heated surfaces of the still.

The improved process of the present invention is particularly advantageous in the cracking of oils in tubular cracking stills, or so-called tube stills, in which the oil is circulated from and to a bulk supply drum through a battery of heating tubes.

In such an apparatus finely divided fuller's earth admixed with fresh feed may be introduced into and intimately admixed with the oil circulating from the bulk supply tank to the heating element and the velocity of circulation maintained sufficiently high to insure the continuance of the fuller's earth in intimate admixture with the oil during its passage through the heating element to the bulk supply tank. A suitable reduction in the velocity of the oil in the bulk supply tank may be utilized to effect segregation and settling, to a greater or lesser

extent, of the fuller's earth with the more objectionable pitch-like constituents absorbed therein and the separating earth may be allowed to accumulate to be withdrawn from time to time, or it may be withdrawn continuously as desired, together with a sufficient quantity of the pitch-laden tar to maintain the concentration of the still charge below the saturation point.

The oil circulating through the heating tubes 10 in contact with the heated tube walls accordingly is intimately admixed with finely divided fuller's earth which selectively absorbs the more objectionable constituents of the cracking reaction as they are formed and while they are 15 therefore in their most active state.

The invention will be further described and illustrated in connection with the accompanying drawing which shows, in a somewhat conventional and diagrammatic manner, one form 20 of tubular pressure still adapted for the practice of the process of the invention, but it is intended and will be understood that the invention is not limited to the specific construction and operation so described.

The apparatus shown comprises a furnace structure 1 having a firebox 2, a vertical throat or uptake 3, a heating flue 4 and stack flue 5. The heating flue 4 is provided with baffles 6 and 7, and a battery of tubes 8 extends vertically therethrough and is provided with upper and lower headers 9 and 10 respectively. Connection 11 is provided whereby a portion of the cooled products of combustion may be returned to flues underneath the firebox 2 at the base of the throat 3 whereby the fresh hot products of combustion from the burner 12 may be somewhat diluted by the recirculated waste heating gases, thus diminishing the temperature and increasing the volume of the heating gases, avoiding overheating of the front tubes in the first pass, more evenly and efficiently heating the tubes throughout and protecting the walls of the firebox and furnace structure. The bulk supply tank or drum 13 is a relatively long closed cylinder arranged with its long axis vertical and with its upper end extending well above the heating element in the furnace. The tank is divided by a vertical partition 14 which extends from the bottom thereof to a level substantially above the top of the heating element 8 dividing the lower portion of the tank 13 into a receiving or separating chamber 15 and an exhaust or supply chamber 16. The receiving compartment 15 is connected to the manifold 17 of the top header 9 by a suitable return flow pipe 18. The supply compartment 16 is connected to the manifold 19 of the lower header 10 by circulating lines 20 and 22 and circulating pump 21. A manhole 23 is provided for cleaning out the compartment 15 when required. The pipe 24 having a valve 25 is connected to the lowest point of the bottom of compartment 15 for charging the still with oil in starting up and pumping out when the operation is discontinued, and a valved branch 26 therefrom connects to a T 27 between the circulating pump 21 and the circulating line 22 for withdrawing oil from these pipes between runs.

The upper end of the tank above the compartments 15 and 16 may, with advantage, be constructed of such volume and suitably equipped to constitute a reflux tower, and a separate reflux tower dispensed with. The upper portion of the tank 13 as illustrated is provided with 75 baffles 28 which may be of the type commonly

employed in reflux towers. The vapor line 29 leading to the condenser is connected directly to the upper end of the tank. The lowermost baffle 28 is so disposed as to discharge any liquid thereon into the supply compartment 16. A valved line 30 and spray head 31 are provided for the introduction of fresh charging stock into the upper end of the reflux tower. The vapor line 29, condenser 32 and receiving drum 33, with its gas release line 34 and distillate draw-off 35, may be of the type commonly employed in connection with cracking stills. A pressure regulating valve 36 in line 29 between the reflux tower and the condenser may be employed for controlling and reducing the pressure in the still and reflux tower independently of the pressure in the condenser or the pressure may be reduced and regulated by suitable valves arranged beyond the condenser. Connection 37 is provided for the introduction of fresh charging stock with finely divided fuller's earth admixed therewith to the circulating connection 22. Valved connections 38, 39 and 40 are provided for withdrawing pitch-laden tar and fuller's earth with the constituents absorbed therein from various levels in the lower portion of the receiving chamber 15.

Briefly, the operation of the illustrated apparatus in accordance with the present invention is as follows: The oil is circulated from the supply compartment 16 in the tank 13 through the heating tubes 8 and thence back to the separating compartment 15 by means of the pump 21, the vaporized oil collecting in the upper portion of the tank 13 and being subjected to reflux condensation therein, and resulting vapors passing through vapor line 29 and condenser 32 to the receiver 33, the liquid distillate being drawn off through connection 35 and uncondensed gases through connection 34. Feed oil may be introduced through connection 34. Feed oil may be introduced through connection 30 into the head of drum 13 to regulate the refluxing operation and through connection 27 into the circulating line 22. Reflux condensate, admixed with any feed oil introduced through connection 30 is returned to the heating element through compartment 16. The pressure within the cracking system may be controlled by valve 36 or by control of the withdrawal of liquid distillate and uncondensed gases from the receiver 33. Condensation may be effected at atmospheric pressure, or at some predetermined intermediate pressure above atmospheric pressure, or at substantially still pressure. The fresh oil introduced through connection 37 contains intimately admixed therewith finely divided fuller's earth and this oil-earth mixture is preferably introduced in the form of a jet, and circulation is maintained by pump 21 at such velocity as to insure the mixture of the fuller's earth and oil and prevent settling while passing through the heating element. The earth or part of the earth may also be supplied to the operation in intimate admixture with oil introduced through pipe 30. The volume of oil maintained in the system during normal operation is such as to keep the separating chamber 15 filled to the top thereof and overflowing into the supply chamber 16 and to keep sufficient oil in the supply chamber 16 to properly maintain the circulation. The exact level of the oil in compartment 16 is not important provided it is sufficient to maintain the proper circulation, but may advantageously be maintained considerably below that

in the receiving chamber 15, as shown in the drawing, so that oil flowing from compartment 15 to compartment 16 passes in a thin sheet or film down the partition 14 which is heated by the oil in the receiving chamber 15 thereby promoting the release of gas and vapors.

The oil from the return pipe 18 is discharged into receiving chamber 15 below the level of the oil therein but at a considerable distance above the bottom of the chamber. The upward movement of the oil in the chamber 15 is relatively slow, due to the relatively large cross section of the column of oil in this chamber as compared to that of the oil stream entering it, thus affording a very favorable condition for the separation of the suspended fuller's earth with the constituents absorbed therein and of any additional carbon or tarry matter formed in the passage of the oil through the heating tubes 8. That portion of the chamber 15 below the connection 18 offers a quiescent zone in which the fuller's earth, carbon and heavier tarry products separating from the circulating oil may settle out and be withdrawn intermittently or continuously during the operation of the still through the draw-off line 40. The oil entering the chamber 15 is thus substantially freed from the heavy matter formed during the cracking operation and the more objectionable sulphur-containing constituents absorbed by the fuller's earth, and only relatively clean oil overflows into the supply chamber 16 to be again recirculated through the heating element.

In the event of stoppage of the tar draw-off line 40, connections 38 and 39 arranged to withdraw oil from higher levels in compartment 15 may be utilized and the run continued. The drum 13 may be constructed of sufficient size to permit operation to be continued for a relatively long time without withdrawing tar, the heavy tarry constituents and fuller's earth accumulating in the lower portion of compartment 15 from which they may be removed through a manhole 23 at the end of the run. Thus even when operating semi-continuously only substantially clean oil is recirculated through the heating tubes, the heavier tarry constituents as well as the more objectionable sulphur containing constituents absorbed by the fuller's earth being separated from the circulating oil and deposited in the settling chamber.

The amount of earth employed will depend upon several factors, in any particular case, these factors including for example the character of the oil subjected to the cracking operation, the degree to which it is cracked or converted into lighter oil, and the rate at which the cracking operation is carried out. In the cracking of gas oil or gas oil character stocks for the production of gasoline, or a gasoline containing pressure distillate, for example, using pressures in the neighborhood of 90 pounds per square inch to 125 pounds per square inch or upward, the amount of earth may vary from about $\frac{1}{8}$ pound per barrel or somewhat less up to as much as 2 pounds per barrel or somewhat more on the total quantity of oil supplied to the operation. In general, it is advantageous to supply the finely divided fuller's earth to the operation in amounts of about $\frac{1}{2}$ pound per barrel of the fresh oil introduced or somewhat less. While relatively coarse grades of fuller's earth, for example 30 mesh or coarser can be employed in carrying out the invention, it is advantageous to use the finer grades of earth, for example 50 or 60 mesh or finer. The

earth may be admixed with the oil or with part of the oil supplied to the cracking operation in any convenient manner. One advantageous method is to maintain in a suitable agitator a relatively concentrated slurry of earth in oil, such as part of the charging stock, and to pump this slurry at a rate appropriate to maintain the amount of earth introduced at the desired value into charging stock on its way to the pressure still.

I claim:

1. In the cracking of heavy hydrocarbon oils for the production of lighter hydrocarbon oils therefrom by distillation under pressure, the improvement comprising circulating the oil through a heating zone and heating it therein to a cracking temperature, maintaining finely divided fuller's earth in intimate admixture with the oil while passing through the heating zone, separating suspended fuller's earth from the circulating oil after it leaves the heating zone, and after such separation recirculating oil therefrom through the heating zone.

2. In the cracking of heavy hydrocarbon oils for the production of lighter hydrocarbon oils therefrom by distillation under pressure, the improvement comprising circulating the oil through a heating zone and heating it therein to a cracking temperature, maintaining finely divided fuller's earth in intimate admixture with the oil while passing through the heated zone, separating suspended fuller's earth from the circulating oil after it leaves the heating zone, withdrawing separated earth and associated material during the operation and after such separation recirculating oil therefrom through the heating zone.

3. In the cracking of heavy hydrocarbon oils for the production of lighter hydrocarbon oils therefrom by distillation under pressure, the improvement comprising circulating a stream of the oil from a bulk supply through a heating zone and back to the bulk supply, heating the oil to a cracking temperature in the heating zone, introducing finely divided fuller's earth into the oil circulating from the bulk supply to the heating zone at a point between the bulk supply and the heating zone, and maintaining the fuller's earth so introduced into the circulating oil in intimate admixture therewith during passage through the heating zone.

4. In the cracking of heavy hydrocarbon oils for the production of lighter hydrocarbon oils therefrom by distillation under pressure, the improvement comprising circulating a stream of the oil

5 from a bulk supply through a heating zone and back to the bulk supply, heating the oil therein to a cracking temperature in the heating zone, supplying fresh oil to the oil circulating from the bulk supply to the heating zone at a point 10 between the bulk supply and the heating zone, introducing finely divided fuller's earth in admixture with fresh oil so supplied to oil circulating from the bulk supply to the heating zone, and maintaining the fuller's earth so supplied in 15 intimate admixture with the oil while passing through the heating zone.

5. In a continuous process for cracking high boiling hydrocarbon oils for the production of lower boiling hydrocarbons therefrom wherein the oil to be cracked is heated to a cracking temperature while circulating it through heating tubes, the improvement which comprises admixing finely divided fuller's earth with oil entering said heating tubes and circulating the oil 20 and fuller's earth through said heating tubes at a rate adequate to maintain the fuller's earth in intimate admixture with the oil and to prevent segregation of the fuller's earth during its entire passage through said heating tubes.

6. In a system for cracking high boiling hydrocarbon oils for the production of lower boiling hydrocarbon oils therefrom wherein the oil is heated to a cracking temperature by circulating it through heating tubes, the improvement which 25 comprises admixing finely divided fuller's earth with oil entering said heating tubes, circulating the oil and fuller's earth through said heating tubes at a rate adequate to maintain the fuller's earth in intimate admixture with the oil and to prevent segregation of the fuller's earth during its entire passage through said heating tubes, adding a mixture of fresh oil and fresh finely divided fuller's earth to the cracking system and 30 discharging residual oil and spent finely divided fuller's earth from said cracking system during the operation of said cracking system.

EUGENE C. HERTHIEL.
